UNITED STATES PATENT OFFICE.

CLIFFORD S. GOBY, OF CLEVELAND, OHIO, ASSIGNOR TO THE ENGINE HOLDINGS COMPANY, OF CLEVELAND, OHIO, A CORPORATION OF OHIO.

INTERNAL-COMBUSTION ENGINE.

1,238,508.

Specification of Letters Patent. Patented Aug. 28, 1917.

Original application filed August 23, 1909, Serial No. 514,098. Divided and this application filed October 18, 1913. Serial No. 795,819.

To all whom it may concern:

Be it known that I, CLIFFORD S. GOBY, a citizen of the United States, residing at Cleveland, in the county of Cuyahoga and State of Ohio, have invented a certain new and useful Improvement in Internal-Combustion Engines, of which the following is a full, clear and exact description, reference being had to the accompanying drawings.

10 This invention relates to valve mechanism for internal combustion engines, the embodiment herein illustrated being applicable to engines of the four cycle type and the valve mechanism being of the sliding sleeve type.

15 Among the objects which it is the aim of my invention to secure are the supply of an adequate amount of combustible fluid at all speeds of the engine; the prevention of leakage in the valve; the provision of a free, 20 full and uninterrupted supply of fluid to and from the inner sleeve of the valve; the balancing of pressure around the moving valve sleeve, preventing the binding of the same and enabling the sleeve to wear evenly 25 in its seat; silence in operation; isolation of the valve shaft chamber from the fluids which enter and leave the cylinder through the valve; ease of assembling and disassembling; the avoidance of any loss of com- 30 pression in the cylinder through the movement of the valve sleeve; efficiency of lubrication; maintaining a fixed density in the combustible fluid entering the cylinder or cylinders; maintaining substantially con- 35 stant the temperature and pressure of the exhaust gases from the cylinder or cylinders; reciprocating the valves without exercising any pumping action on the fuel supply; and generally providing a valve con- 40 struction whereby great efficiency is secured in the operation of the engine with which it may be associated. Further and more limited objects of the invention will appear hereinafter; and the invention may be de- 45 fined generally as consisting of the combina- tions of elements embodied in the claims hereto annexed and illustrated in the drawings accompanying and forming part here- 50 of, wherein Figure 1 represents a view, partly in section and partly in elevation, of an engine cylinder having my valve mech- anism applied thereto, part of the crank case being shown; Fig. 2 represents a trans- 55 verse sectional view corresponding to the

line 2—2 of Fig. 1; Fig. 3 is a view, partly in section and partly in elevation, of a driving connection between the engine shaft and the valve or "lay" shaft; Fig. 4 is an elevation of one of the valve sleeves, with its connecting rod; Fig. 5 a sectional view of such valve corresponding to the line 5—5 of Fig. 4; Fig. 6 an elevation of the internal sleeve or liner for the valve; Fig. 7 a sectional view of the said sleeve or liner corresponding to the line 7—7 of Fig. 6; and Fig. 8 a side elevation of a four-cylinder engine having my valve mechanism applied thereto.

Describing by reference characters the parts illustrated herein, 1 denotes a part of the crank case, 2 the engine crank shaft, 3 a connecting rod projecting from one of the cranked portions of said shaft and having its upper end connected to a piston 4 within a cylinder 5. It will be understood that a multi-cylinder engine may be employed and a four-cylinder engine is illustrated herein. For convenience of illustration and description, a single cylinder only and its coöperating parts are shown in detail.

Surrounding the upper portion of each cylinder is a water jacket 6, said jacket being conveniently secured in place by means of a nut 7 threaded upon the lower portion of each cylinder and engaging at its upper end a washer 8 interposed between the nut and an inwardly projecting bearing sleeve 9 formed on the water-jacket casting. The upper section 10 of each water jacket is provided with a flange 11 whereby it may be supported upon a flange 12 at the upper end of the lower water-jacket section. The section 10 is conveniently cast with the upper end of the cylinder proper, and a removable cap 13 having a cooling-liquid outlet connection 14 is detachably secured to the top of the section 10, as by means of bolts 15.

The construction whereby the water jacket is provided forms no part of the invention in this case, the same constituting the subject matter of my application No. 514,098, filed August 23, 1909 of which this application is a division.

At one side of and preferably cast integral with each cylinder, are two cylindrical valve casings or chambers 16. The water

2

jacket, to which reference has been made hereinbefore, is extended around the upper portions of the valve casings, as shown at 17, and the inlet duct for the cooling liquid 5 communicates with this portion of the jacket, as indicated at 18. As illustrated herein, the axes of the valve casings are substantially parallel with the axes of their correspondingly cylinders. Each cylinder 10 is provided with an expanding or fan shaped duct 19 projecting therefrom and preferably cast with and forming part of the casings 16 of an inlet and an exhaust valve. The outer wall of the duct is projected outwardly around the outer sides of the valve sleeves, whereby a port 20 is provided entirely around each valve sleeve, enabling the pressure in the cylinder and in the duct 19 to be equalized around such 15 sleeves. The port 20 of each of the valves 20 forms in effect part of the duct 19.

Slidably mounted within each valve casing 16 is a sliding valve sleeve 21. This sleeve is provided, intermediate of its ends, 25 with a segmental series of ports 22 which are adapted to register with the ports 20 when the sleeve is in an intermediate position, as will appear more particularly from Fig. 1. The lower end of each sleeve is 30 operated by a connecting rod 23, the lower end whereof is mounted upon a wrist pin 24 projecting from the cranked lay shaft 25. This shaft is shown as mounted within a casing 26 which receives the lower ends 35 of the valve casings 16 and is in open communication with the same. This casing is adapted to contain oil whereby the valve parts thereabove may be lubricated by the "splash" system and is shown as provided 40 with a removable cover 27. As will appear from this figure, the crank shaft 25 is offset axially from the valve casings 16, whereby adjustment for timing may be conveniently obtained.

45 Suspended within each valve casing and forming therewith an annular guide for the sliding valve sleeve 21, is the inner sleeve or bushing 28. These inner sleeves or bushings are shown as suspended from the tops 50 of their respective valve casings, each sleeve or bushing being provided with a flange 29 whereby it is mounted upon the top of its respective valve casing. At its upper end, each of the sleeves or bushings is contracted 55 in diameter, as shown at 28^a, to provide with the upper end of the outer valve casing an oil chamber 29 with which the oil duct 30 communicates. The sleeve or bushing 28 is provided with a segmental series of ports 31 60 which register with the port 20 in the corresponding valve casing as well as with the ports 22 in the sliding sleeve valve as the latter is reciprocated within the annular seat formed between the sleeves 16 and 28. Below the ports 31, and preferably immedi-

ately below the same, the sleeve or bushing 28 is provided with a partition 32 forming an abutment, which extends across the bore of the said sleeve or bushing and isolates the upper portion thereof from the lower portion 70 of the valve casing 16 and from the casing 26 containing the lubricating oil. To further isolate the fluids within the interior of the inner sleeve or liner 28 from the oil chamber and to prevent the said fluids from 75 coming in contact with such oil, packing rings 33 are provided in the outer surface of this liner or bushing above and below the ports 31 and below the abutment 32.

The duct 19, it will be observed, is common to both of the valves and serves both as an inlet and an exhaust duct, and a suitable inlet or exhaust duct 33 is secured above the flanged end 29 of the appropriate inner sleeve or bushing 28 and communicates 85 freely with the interior thereof.

One end of the shaft 2 is provided with a spiral gear 34 meshing with a similar gear 35 on a shaft 36, the upper end whereof is provided with a spiral gear 37 meshing with 90 a similar gear 38 on the lay shaft 25. These gears are made of such size that the inlet and exhaust valves 21 make one complete stroke for every four complete strokes of the piston 4.

95 In operation the engine described herein operates in the same manner as the ordinary four-cycle engine, the exhaust valve being closed when the inlet valve is open. After the admission takes place, a compression follows, and the inlet valve is then closed, the exhaust valve being placed so as to be closed at this time also. The explosion next follows, with both inlet and exhaust valves closed and, at the end of the explosion stroke 100 of the piston 4, the inlet valve will have reached the uppermost limit of its stroke. The exhaust now takes place, with the inlet valve closed and the exhaust valve open and, following this, admission takes place with 105 the inlet valve open and the exhaust valve closed, as will be understood by those skilled in this art. From the construction and arrangement of parts, it will be evident that the inlet and exhaust valves are open when 110 these valves are each in an intermediate position and that the ports thereof are opened and closed by a continuous movement of their respective valves in the same direction, such opening and closing occurring during 115 a single cycle of the four-stroke engine, the valve movements in succeeding cycles being in opposite directions; also that the ports in each tubular valve or valve sleeve are caused to register with the ports in the valve casing only during alternate reciprocations of the piston.

120 It will be observed that, by the arrangement of the outer valve casings and the inner liners or bushings, a flue or chimney is 125

provided in each exhaust valve for the exhaust gases, which flue or chimney extends above and away from the ports in the liner or bushing and that extended insulating films of oil are provided and maintained above and below the ports in the liner and in the surrounding valve casing. It will be evident that, by reason of this construction and arrangement of parts, the temperature within the liner will be maintained substantially constant whereby, in the case of an exhaust valve, like constant temperature and constant pressure may be maintained in the exhaust gases with corresponding uniformity in operation, particularly in the scavenging of the combustion space of the engine. Furthermore, the cooling liquid in a jacket surrounding the cylinders is largely protected against the heating action of these gases. In the case of an inlet valve, the entering combustible fluids are subjected to a substantially constant temperature enabling a fixed density to be maintained therein.

Having thus described my invention, what I claim is:—

1. In an internal combustion engine, the combination of a cylinder, a pair of annular valve casings on the same side of the cylinder and each having a port, there being a duct extending from the cylinder to said casings and communicating with said ports, a valve sleeve slidably mounted in each of the casings, each of said sleeves being provided with a port adapted to register with the port in its casing, a shaft, and a driving connection between said shaft and each of the valve sleeves.

2. In an internal combustion engine, the combination of a cylinder, a pair of valve chambers located on the same side of the cylinder and each having a port, there being a duct extending between the cylinder and the valve chambers and communicating with said ports, means coöperating with each valve chamber to form therewith an annular seat, a valve sleeve in each seat controlling communication between the valve chamber and the cylinder and duct, a shaft, and means connecting each valve with the shaft.

3. In an internal combustion engine, the combination of a plurality of cylinders, a plurality of valve chambers corresponding to said cylinders, there being ducts connecting said chambers with said cylinders, an open-ended tubular valve in each chamber having a port adapted to communicate with the corresponding duct, all of said valves having their axes in a common plane, and a shaft connected with all of said valves and offset from the plane of the axes thereof.

4. In an internal combustion engine, the combination of a plurality of cylinders, a

plurality of valve chambers corresponding to said cylinders, there being ducts connecting said chambers with their respective cylinders, a tubular valve in each chamber adapted by its movement to control the flow of fluid through its corresponding duct, a liner or bushing within each tubular valve and forming with the valve chamber an annular guideway for each valve, all of said valves having their axes in a common plane, and a shaft connecting with all of said valves and offset from the plane of the axes thereof.

5. In an internal combustion engine, the combination of a plurality of cylinders, an inlet and an exhaust valve chamber for each cylinder and located on the same side thereof, said valve chambers having each a port and there being a duct extending from each cylinder and communicating with the valve chamber ports corresponding thereto, a tubular valve in each chamber adapted by its movement to control the port thereof, an internal bushing or liner within each chamber and forming therewith an annular guide for the valve, and means within each liner or bushing for directing the fluids passing through the port of its valve chamber.

6. In an internal combustion engine, the combination of a cylinder, a piston therein, a shaft operatively connected with said piston, a valve chamber comprising an outer sleeve provided with a port, there being a duct establishing communication between said port and the cylinder, a valve sleeve slidable within the first-mentioned sleeve and provided with a port adapted to register with the former port, and a sleeve mounted within the valve sleeve and provided with a port complementary to the port in the first-mentioned sleeve and having a partition extending across its bore, means for anchoring the last mentioned sleeve in position, and a driving connection between said shaft and the valve sleeve.

7. In an internal combustion engine, the combination of a cylinder, a valve chamber comprising an outer sleeve provided with a port, there being a duct establishing communication between said port and the cylinder, a valve sleeve slidable within the first-mentioned sleeve and provided with a corresponding port adapted to register with the former port, a sleeve mounted within the valve sleeve and provided with a port intermediate of the ends thereof and complementary to the port in the first-mentioned sleeve and having a partition extending across its bore, an extension projecting from one end of the last-mentioned sleeve, means securing said extension to a fixed part of the engine, a shaft, and a driving connection between said shaft and the valve sleeve.

8. In an internal combustion engine, the combination of a cylinder, a piston therein,

- a shaft operatively connected to said piston, a valve chamber comprising an outer sleeve, a fluid duct connected with an end of said sleeve, said sleeve being provided with a 5 port intermediate of the ends thereof, there being a duct extending between the port in said sleeve and the cylinder, a valve sleeve slidable within the first-mentioned sleeve and provided with a port intermediate the 10 ends thereof adapted to register with the former port, a sleeve anchored within the valve sleeve and provided intermediate of its ends with a port adapted to register with the port in the valve sleeve and with a partition, a shaft connected with said valve 15 sleeve, and driving connections between the first and second shafts.
9. In an internal combustion engine, the combination of a cylinder, a valve chamber 20 comprising an outer sleeve provided with a port communicating with a duct extending to said cylinder, a valve sleeve slidable within the first-mentioned sleeve and provided with a port adapted to register with the 25 port in the former sleeve, a sleeve anchored within the valve sleeve and provided with a port adapted to register with the ports in the former sleeves and also provided with a partition, the first mentioned sleeve being 30 provided with a chamber surrounding the portion of the valve sleeve which is remote from the cylinder, a shaft, and a driving connection between said shaft and the valve sleeve.
- 35 10. In an internal combustion engine, the combination of a cylinder, a valve chamber comprising an outer sleeve having one or more ports intermediate of the ends thereof, there being a duct extending between said 40 port or ports and the cylinder, a valve sleeve slidably mounted within the former sleeve and provided intermediate of its ends with one or more ports corresponding to the port or ports in the former sleeve and provided 45 on opposite sides of said port or ports with suitable packing rings, a sleeve anchored within the valve sleeve and having one or more ports complementary to the port or ports in the first-mentioned sleeve, and means 50 for reciprocating the movable sleeve.
11. In an internal combustion engine, the combination, with a cylinder and piston, of a valve casing having a port communicating with the cylinder, a tubular valve in said 55 casing having a port therein adapted to register with the casing port, a shaft driven by said piston, and means including reduction gearing, for moving said valve by said shaft at a speed slower than the piston speed 60 and in opposite directions during succeeding cycles in the operation of the engine to open and close the port during each of such cycles by a valve movement in one direction.
12. In an internal combustion engine, the 65 combination, with a cylinder and a valve casing having a port communicating with the cylinder, of a reciprocating valve having a port adapted to register with the first mentioned port, and means for moving the valve to open and close the ports by a continued movement in the same direction during a single cycle of the engine, the valve movements in succeeding cycles of the engine being in opposite directions.
13. In an internal combustion engine, the 75 combination of a cylinder, a valve casing having a port intermediate of its ends communicating with said cylinder, a piston in the cylinder, a tubular valve in said casing having a port intermediate of its ends 80 adapted to register with the valve casing port, and driving connections for said valve whereby the port therein is caused to move into and out of registration with the cylinder port by a continuous sliding movement of 85 the valve, such registration occurring only during alternate reciprocations of the piston.
14. In an internal combustion engine, the combination of a cylinder, a pair of valve casings each having a port intermediate of 90 its ends communicating with said cylinder, a piston in the cylinder, a tubular valve in each of said casings and each having a port intermediate of its ends adapted to register with its valve casing port, and driving connections whereby the ports in said valves are caused to move into and out of registration with their respective cylinder ports each 95 by a continuous movement in the same direction and to register alternately with their 100 respective ports during successive reciprocations of the piston.
15. In an internal combustion engine, the combination of a cylinder, a piston therein, a shaft operatively connected with said piston, a pair of valve casings each having a port intermediate of its ends communicating with said cylinder, a tubular valve slidably mounted in each casing and each having 105 a port intermediate of its ends adapted 110 to register with its casing port, a fluid duct communicating with the interior of each valve, a shaft, means connecting each valve with said shaft, such connections being angularly spaced, and a four-to-one reduction 115 drive between the first-mentioned and the last mentioned shaft.
16. In an internal combustion engine, the combination of a cylinder, a piston therein, a valve casing having a port intermediate of 120 its ends communicating with said cylinder, a liner within said casing and forming therewith an annular valve seat and having a port corresponding to the port in the casing, a tubular valve reciprocably mounted in said 125 seat and having a port intermediate of its ends adapted to register with the former ports, a fluid duct communicating with the interior of said liner, and connections for driving said valve whereby the ports are 130

- caused to register only during alternate reciprocations of the piston.
17. In an internal combustion engine, the combination of a cylinder, a piston therein, a cylindrical valve chamber separate from the cylinder and having concentric spaced walls each provided with a port intermediate the ends thereof adapted to communicate with the cylinder, a cylindrical valve movable longitudinally in the seat formed between the said walls and having a port intermediate of its ends adapted to register with the former ports, and driving connections between the piston and the valve for reciprocating the latter.
18. In an internal combustion engine, the combination of a cylinder, a valve casing having a port communicating with said cylinder, a tubular valve slidably mounted within said casing and having a port intermediate of its ends arranged to register with the casing port, a fluid duct in open communication with the interior of said valve, an abutment located within said valve on the side of the valve port remote from the fluid duct connection therewith, and means for reciprocating said valve.
19. In an internal combustion engine, the combination of a cylinder, a valve casing having a port communicating with said cylinder, a tubular valve slidably mounted within said casing and having a port intermediate of its ends arranged to be brought into register with the casing port, a fluid duct in open communication with the interior of said valve, an abutment disconnected from said valve and located on the side of the casing port opposite the point of introduction of fluid fuel into the interior of the valve, and means for reciprocating said valve.
20. In an internal combustion engine, the combination of a cylinder, a valve casing having a port communicating with the cylinder, a tubular valve reciprocably mounted in said casing and having a port adapted to register with the former port, a tubular liner within the valve having a port arranged to register with the former ports and having an abutment at one side of its port, a fluid duct communicating with the interior of the liner, and means for reciprocating the valve.
21. In an internal combustion engine, the combination of a cylinder, a valve casing separate from the cylinder and having a port communicating with said cylinder, a tubular valve slidably mounted within said casing and having a port intermediate of its ends arranged to be brought into and out of register with the casing port during each sliding movement, a piston in the cylinder, a shaft connected thereto, a shaft offset from the plane of the valve axis and connected to said valve, and reduction gearing for driving the second shaft from the first-mentioned shaft.
22. In an internal combustion engine, the combination of a cylinder, a valve casing having a port communicating with the cylinder, a tubular valve slidably mounted within said casing and having a port intermediate of its ends arranged to register with the former port, a tubular liner within the valve having a port arranged to register with the former ports and provided on one side of its port with an abutment, means for supplying fluid fuel to the interior of said liner, and means for reciprocating said valve.
23. In an internal combustion engine, the combination of a cylinder, a pair of valve casings each having a port communicating with the cylinder, a tubular valve reciprocably mounted in each casing and each having a port intermediate of its ends arranged to register with its casing port, a tubular liner within each valve and each having a port adapted to register with the former ports and provided each with an abutment on one side of its port, means for supplying fluid fuel to the interior of one of said liners, an exhaust duct communicating with the interior of the other liner, a shaft offset from the plane of the axes of said valves, a connection between each valve and said shaft, said connections being angularly spaced, a piston in the cylinder, a shaft connected thereto, and a speed reduction drive connection between the latter shaft and the former shaft.
24. In an internal combustion engine, the combination of a cylinder, a valve casing having a port communicating with said cylinder, a tubular valve slidably within said casing and having a port adapted to register with the former port, a liner or bushing within said valve, a fluid duct communicating with the liner or bushing, said liner or bushing having a port adapted to register with the former ports, the casing having a chamber surrounding a portion of the valve which is remote from the cylinder and communicating with said cylinder and subjecting the exterior of the valve to cylinder pressure, and means for reciprocating said valve.
25. In an internal combustion engine, the combination of a cylinder, a valve casing separate from the cylinder and having a port communicating with said cylinder, a tubular valve reciprocably mounted within said casing and having a port adapted to communicate with the former port, a fluid duct communicating with the interior of the valve, and means within the valve and non-movable therewith for deflecting the fluid passing through its port.
26. In an internal combustion engine, the combination of a cylinder having a duct communicating therewith, a pair of valve

- casings extending across said duct and each having a port communicating therewith, a tubular valve reciprocably mounted in each casing and each having a port adapted to register with its casing port, the duct communicating with that portion of each valve casing which is remote from the cylinder whereby the pressure on opposite sides of each valve is balanced, connections for supplying fluid fuel to the interior of one of said valves and through its port, and connections permitting the exhaust gases from the cylinder to escape from the interior of the other valve.
15. 27. In an internal combustion engine, the combination of a cylinder having a combined inlet and exhaust duct extending therefrom, a pair of valve casings each having a portion within said duct and each 20 provided with a port extending substantially circumferentially around the same and within the said duct, a tubular valve slidably mounted in each casing and having each a port arranged to be brought into 25 communication with its casing port, means for supplying fluid fuel to the interior of one of said valves, an exhaust duct leading from the interior of the other valve, and means for reciprocating said valves.
30. 28. In an internal combustion engine, the combination of a cylinder, an open bottom valve casing extending substantially parallel with said cylinder and having a port intermediate of its ends communicating therewith, a tubular valve in said casing having a port adapted to communicate with the former port, a shaft beneath said valve and connected thereto, an abutment in said valve and non-movable therewith, and located beneath the first-mentioned port, and a chamber for said shaft communicating with the bottom of the valve casing.
35. 29. In an internal combustion engine, the combination of a cylinder, a valve casing at one side of and extending substantially parallel with said cylinder and having an open bottom and provided with a port intermediate of its ends communicating with said cylinder, an open-ended tubular valve slidably mounted within said casing and having a port in its wall adapted to register with the former port, a fluid duct communicating with the interior of the valve casing above the top of the valve, a chamber beneath said valve casing and communicating therewith, a shaft in said chamber, a connection between said shaft and said valve, and an abutment extending across said valve below the port thereof and operatively disconnected therefrom.
40. 30. In an internal combustion engine, the combination of a cylinder, a valve casing having a port adapted to communicate with said cylinder, a tubular valve in said casing having a port in its wall adapted to register with the casing port, an abutment within said valve at one side of the port therein and non-movable with said valve, a fluid duct adapted to communicate with said valve on the ported side of the abutment therein, a chamber on the opposite side of the abutment, a shaft in said chamber, and a connection between the shaft and the valve.
45. 31. In an internal combustion engine, the combination of a cylinder, a cylindrical valve chamber extending substantially parallel with the cylinder and having a port intermediate of its ends communicating with the cylinder, a fluid duct communicating with the upper portion of said chamber, a tubular valve slidably mounted in the valve chamber and having a port in its wall adapted to register with the valve chamber port, a chamber beneath said valve chamber, a shaft in the latter chamber, a connection between said shaft and said valve, and a tubular liner within the valve having a port intermediate of its ends adapted to register with the former port and provided with an abutment below its port.
50. 32. In an internal combustion engine, the combination of a cylinder, a cylindrical valve casing having a port intermediate of its ends adapted to communicate with said cylinder, a cylindrical valve in said casing having a port intermediate of its ends adapted to register with the former port, a liner sleeve in said valve having a port intermediate of its ends adapted to register with the former ports and non-movable with said valve and forming with the casing an annular seat for the valve, an abutment in said liner sleeve at one side of the port therein, a fluid duct adapted to communicate with said liner sleeve on the ported side of the same, a chamber on the opposite side of the abutment from the fluid duct connection, a shaft in said chamber, and a connection between the shaft and the valve.
55. 33. In an internal combustion engine, the combination of a cylinder, an annular valve seat comprising inner and outer spaced cylindrical walls having registering ports adapted to communicate with the cylinder, a cylindrical valve in the seat between said walls and having a port adapted to register with the former ports, a fluid duct adapted to communicate with the interior of the seat at one side of the port in the inner wall thereof, and an abutment extending across the interior of the seat on the side of the port opposite the fluid duct connection therewith.
60. 34. In an internal combustion engine, the combination of a cylinder, a piston therein, a shaft connected to said piston, a pair of valve casings separate from the cylinder and each having a port adapted to communicate with said cylinder, an open-ended tubular valve longitudinally movable in each valve

- casing and each having a port intermediate of its ends adapted to communicate with its casing port, an abutment within each valve at one side of the port therein and non-
 5 movable therewith, a fluid supply duct communicating with one of the valve casings and adapted to supply fluid into the open end of the valve therein, a fluid outlet duct communicating with the other casing and
 10 adapted to receive gases discharged through the open end of the valve therein, a shaft connected to said valves, and a four-to-one reduction drive between the shafts.
 15 35. In an internal combustion engine, the combination of a cylinder, a piston therein, a shaft, a connection between said piston and said shaft, a valve chamber comprising an outer sleeve provided with a port, there being a duct establishing communication between said port and the cylinder, a valve sleeve slidable within the first-mentioned sleeve and provided with a corresponding port adapted to register with the former port, a sleeve mounted within the valve sleeve and provided with a port intermediate of the ends thereof and complementary to the port in the first-mentioned sleeve and having a partition extending across its bore adjacent to said port, an extension projecting from one end of the last-mentioned sleeve, means securing said extension to a fixed part of the engine, a second shaft, a driving connection between said shaft and the valve sleeve, and reduction gearing connecting the latter shaft and the first-mentioned shaft.
 20 36. In an internal combustion engine, the combination of a cylinder, a piston in said cylinder, a shaft, a driving connection between said shaft and said piston, a pair of sleeves each having a port communicating with said cylinder, said sleeves being located on the same side of the cylinder, a sleeve slidably mounted in each of the former sleeves, and each of the latter sleeves being provided with a port adapted to register with the port in its surrounding sleeve, a lay shaft, a driving connection between said shaft and each of the movable sleeves, said connections being angularly spaced, and four-to-one reduction gearing connecting the first mentioned shaft and the lay shaft.
 25 37. In an internal combustion engine, the combination of a cylinder, a valve chamber comprising an outer sleeve provided with a port communicating with said cylinder, a valve sleeve slidable within the first mentioned sleeve and provided with a port adapted to register with the port in the former sleeve, a sleeve anchored within the valve sleeve and provided with a port adapted to register with the ports in the former sleeves, connections for supplying fluid fuel to the interior of the last mentioned sleeve and through the port thereof,

a piston in said cylinder, a shaft operatively connected with said piston, and reduction gearing connecting said shaft and the slideable valve sleeve.

38. In an internal combustion engine, the combination of a cylinder, a valve chamber comprising an outer sleeve provided with a port communicating with said cylinder, a valve sleeve slidable within the first mentioned sleeve and provided with a port adapted to register with the port in the former sleeve, a sleeve anchored within the valve sleeve and provided with a port adapted to register with the ports in the former sleeves, connections for supplying fluid fuel to the interior of the innermost sleeve and through the port thereof, a piston in said cylinder, a shaft, connections between said shaft and said piston, a lay shaft offset with respect to the axes of said sleeves, a connection between said shaft and the movable sleeve, and reduction gearing connecting said shafts.

39. In an internal combustion engine, the combination of a cylinder, a piston therein, a shaft, a driving connection between said shaft and said piston, a sleeve located at one side of said cylinder, said sleeve having a port communicating with the cylinder, a sliding sleeve valve mounted within the former sleeve and provided with a port adapted to register with the port in the former sleeve, a lay shaft, a driving connection between the lay shaft and the sliding sleeve, reduction gearing connecting the latter shaft and the first mentioned shaft, a sleeve anchored within the sliding sleeve and provided with a port adapted to register with the ports in the former sleeves, the last mentioned sleeve being provided with a partition extending across its bore at one side of the port therein, and connections for supplying fluid fuel longitudinally of the last mentioned sleeve at the opposite side of said partition.

40. In an internal combustion engine, the combination of a cylinder, a valve casing comprising a sleeve having a port adapted to communicate with the cylinder, a valve sleeve slidable within the first mentioned sleeve and adapted by its movements to control the flow of fluid through the port thereof, a tubular lining or bushing within the valve having a port adapted to register with the valve casing port and having an abutment below its port, and means whereby said sleeve may be suspended from the upper portion thereof.

41. In an internal combustion engine, the combination of a cylinder, a valve casing comprising a sleeve provided with a port adapted to communicate with said cylinder, a valve sleeve slidable within the outer sleeve and adapted by its movement to control the flow of fluid through the port

thereof, and an inner sleeve or bushing within said valve sleeve having a port adapted to communicate with the valve casing port and an abutment below its port, said inner sleeve or bushing having a flange at its upper end adapted to overhang the valve sleeve and to suspend the liner or bushing from the top of the valve casing.

42. In an internal combustion engine, the combination of a cylinder, a valve casing comprising a sleeve having a port adapted to communicate with the cylinder, a sliding sleeve valve within the first-mentioned sleeve and adapted by its movement to control the flow of fluid through its port, an inner sleeve or bushing within the valve sleeve and forming with the outer sleeve an annular seat for the valve sleeve, the inner sleeve or bushing having a port adapted to communicate with the first mentioned port and having an abutment below its own port, said sleeve or bushing having an outwardly projecting annular flange at its top whereby it is suspended within the valve casing, and a fluid inlet communicating with the space between the valve casing and the lining sleeve or bushing.

43. In an internal combustion engine, the combination of a cylinder, a valve casing separate from the cylinder and having a port adapted to communicate therewith, a sliding sleeve valve reciprocably mounted in said casing and adapted to control the port in said casing, and means within said valve and operatively disconnected therefrom for isolating the space on one side of the casing port from the space on the opposite side thereof.

44. In an internal combustion engine, the combination of a cylinder, a valve casing separate from the cylinder and having a port adapted to communicate therewith, a sliding sleeve valve within the casing adapted to control said port, means located on one side of the port for operating said valve, and means within said valve and operatively disconnected therefrom for isolating the operating means from the fluids passing through said port.

45. In an internal combustion engine, the combination of a cylinder, an inlet valve chamber and an exhaust valve chamber separate from the cylinder and located on the same side thereof and each having a port adapted to communicate with the cylinder, a sliding sleeve valve within each casing and adapted to control respectively the flow of inlet and exhaust gases therethrough, and means located within each valve and operatively disconnected therefrom for directing the gases respectively into the cylinder and into the exhaust connection.

46. In an internal combustion engine, the combination of a cylinder, an inlet valve chamber and an exhaust valve chamber sep-

arate from the cylinder and each having a port adapted to communicate with the cylinder, a sliding sleeve valve within each casing and adapted to control respectively the flow of inlet and exhaust gases therethrough, and means located within each valve and operatively disconnected therefrom for directing the gases respectively into the cylinder and into the exhaust connection.

47. In an internal combustion engine, the combination of a cylinder, a valve casing separate from the cylinder and having a port intermediate of its ends, a valve sleeve reciprocably mounted in said casing and adapted to control said port, and a hollow liner or bushing within the valve casing and forming therewith an annular seat for the valve and having a port intermediate of its ends adapted to communicate with the casing port and comprising a wall extending away from the aforesaid ports to form an inclosed passageway for and to prevent the cooling of the exhaust gases.

48. In an internal combustion engine, the combination of a cylinder, a valve casing separate from the cylinder and having a port adapted to communicate therewith, a sliding sleeve valve reciprocably mounted within the casing and adapted to control said port, a hollow liner or bushing within the valve casing and forming therewith an annular seat for said valve and provided with a port adapted to register with the first mentioned port, the valve sleeve having a port intermediate of its ends so that extended oil films may be maintained, above and below the port, between the inner and the outer surface of the valve sleeve and the valve liner and casing, thereby to provide insulating layers for maintaining substantially constant the temperature within said liner or bushing.

49. In an internal combustion engine, the combination of a cylinder, an exhaust valve chamber separate from the cylinder and provided with a port adapted to communicate therewith, a sliding sleeve valve reciprocably mounted within the casing and adapted to control said port, and a hollow liner within the valve and forming with the casing an annular seat for the valve, said liner being provided with a port adapted to communicate with the casing port and the liner extending away from the port therein to provide a flue or chimney for the exhaust gases, whereby a substantially constant pressure may be maintained therein and the combustion space of the engine be effectually scavenged.

50. In an internal combustion engine, the combination of a cylinder, an inlet valve chamber separate from the cylinder and provided with a port adapted to communicate therewith, a sliding sleeve valve re-

5 ciprocably mounted within the casing and adapted to control said port, and a hollow liner within the valve and forming with the casing an annular seat or guide for the valve, said liner being provided with a port adapted to communicate with the casing port and extending away from said port toward the fuel supply connection and adapted to receive combustible fluid from 10 such connection, whereby oil films may be maintained between the inner and the outer surface of the valve sleeve and the liner and the casing, said films extending from the liner port toward the inlet connection, 15 thereby to maintain a fixed density in the entering combustible fuel.

51. In an internal combustion engine, the combination of a cylinder, a valve casing separate from the cylinder and having a 20 port intermediate of its ends, a valve sleeve reciprocably mounted in said casing and adapted to control said port, and a hollow liner or bushing within the valve casing and forming therewith an annular seat for the 25 valve extending away from said port to form an inclosed passageway for fluids entering or leaving the cylinder.

52. In an internal combustion engine, the combination of a cylinder, a valve casing 30 separate from the cylinder and having a port adapted to communicate therewith, a sliding sleeve valve reciprocably mounted within the casing and adapted to control said port, a hollow liner or bushing within the valve 35 casing and forming therewith an annular seat for said valve and extending away from said port, the valve sleeve being adapted to reciprocate in the space between the liner or bushing and the casing, whereby extended 40 oil films may be maintained upon the inner surface of the casing and the outer surface of the liner or bushing thereby to provide insulating layers for maintaining substantially constant the temperature within said 45 liner or bushing.

53. In an internal combustion engine, the combination of a cylinder, an exhaust valve chamber separate from the cylinder and provided with a port adapted to communicate 50 therewith, a sliding sleeve valve reciprocably mounted within the casing and adapted to control said port, and a hollow liner within the valve and forming with the casing an annular seat for the valve, said liner 55 extending away from the port to provide a flue or chimney for the exhaust gases, whereby a substantially constant pressure may be maintained therein and the combustion space of the engine be effectually scavenged.

54. In an internal combustion engine, the combination of a cylinder, an inlet valve chamber separate from the cylinder and provided with a port adapted to communicate

therewith, a sliding sleeve valve reciprocably mounted within the casing and adapted 65 to control said port, and a hollow liner within the valve and forming with the casing an annular seat or guide for the valve, said liner extending away from said port toward the fuel supply connection and adapted to receive 70 combustible fluid from such connection, whereby oil films may be maintained between the inner and the outer surface of the valve sleeve and the liner and the casing, said films extending from the casing port 75 toward the inlet connection, whereby to maintain a fixed density in the entering combustible fuel.

55. In an explosion engine, in combination, a cylinder, a cylindrical valve chamber 80 connected with said cylinder by way of a port, a tube closed at one end concentrically disposed in said valve chamber, a sleeve valve sliding between said tube and the walls of said chamber, said tube having a side 85 opening substantially registering in position and extent with said port, said sleeve valve simultaneously controlling said port and said side opening, a piston in said cylinder, and means for operatively connecting said 90 piston with said sliding valve.

56. In an explosion engine, in combination, a cylinder, a cylindrical valve chamber connected with said cylinder by means of a port, a tube securely mounted in said valve 95 chamber, said tube being concentric with said chamber and being closed at one end, the other end being exposed to the atmosphere, and having a port substantially registering in position and extent with said 100 first named port, and a sleeve valve sliding between said tube and the walls of said chamber.

57. In an explosion engine, in combination, a cylinder, a piston operating in said 105 cylinder, a cylindrical valve chamber connected with said cylinder by means of a port, a tube securely mounted in said valve chamber, said tube being concentric with said chamber and being closed at one end, the 110 other end being connected with the combustible mixture supply, and having a port substantially registering in position and extent with said first named port, a sleeve valve sliding between said tube and the 115 walls of said chamber, and means for operatively connecting said sleeve valve with the piston.

In testimony whereof, I hereunto affix my signature in the presence of two witnesses.

CLIFFORD S. GOBY.
